ADJUSTABLE CAP

Eugene F. Meyer, Louisville, Ky., assignor to
Town Talk Manufacturing Company, Louisville, Ky.

Application November 14, 1932
Serial No. 642,655

5 Claims. (Cl. 2—197)

This invention relates to headwear and has special reference to an adjustable cap.

Heretofore adjustable caps have been made wherein the head band could be adjusted to suit heads of different sizes by means of straps having their forward ends adjustably connected in front of the cap above the visor. It has been found that the public objected to the display of the adjustable feature because of its tendency to detract from the neat appearance of the cap.

Other caps of adjustable character have had the straps connected rearwardly to the opposite sides of the head band inside of the cap, the straps being held between the forward parts of the head band and sweat band and having their forward ends adjustably connected, this being done to avoid the appearance of the adjusting straps on the outside of the cap. These caps have been found to produce unsightly wrinkles over the visor upon being adjusted to the smaller sizes and were objectionable both on account of such appearance and because of discomfort when worn.

One important object of the present invention is to provide an improved form of adjustable cap wherein there is no unsightly appearance of the adjusting straps outside of the cap and wherein the head band is not wrinkled when the cap is adjusted to the smaller sizes.

A second important object of the invention is the provision of an improved form of adjustable cap wherein the adjusting device is so concealed as to be invisible when the interior of the cap is seen even if the sweat band is turned down and yet the adjusting device is readily accessible when adjustment is desired.

With the above and other objects in view as will be hereinafter apparent, the invention consists in general of certain novel details of construction and combinations of parts hereinafter fully described, illustrated in the accompanying drawing and specifically claimed.

In the accompanying drawing like characters of reference indicate like parts in the several views, and:

45 Figure 1 is a bottom plan view of a cap constructed in accordance with this invention.

Figure 2 is a detail side view of that portion of one side of the cap to which an adjusting strap is attached.

50 Figure 3 is a section, slightly enlarged, on the line 3—3 of Figure 2.

Figure 4 is an enlarged detail view of the front part of the cap from the bottom showing the sweat band turned down and the lining drawn back to

55 expose the adjustment device.

Figure 5 is a section on the line 5—5 of Figure 4.

Figure 6 is an enlarged elevational view of the front ends of the adjusting straps.

Figure 7 is a detail side view of a portion of the cap with the adjusting strap omitted to better show the arrangement of the V-notch and the slot used herein.

Figure 8 is a view similar to Figure 3 but showing a modification adapted to be used with unlined caps such as are used in summer.

In the embodiment of the invention shown in the drawing a cap having a crown 10, head band 11 and visor 12 is illustrated, the appearance being that of the usual style now in common use. This cap is completely lined with a lining 13 which is sewed to the body of the cap entirely around its edge except for a loose or full portion 14 at the front, the edge of this part being left free and for similar loose portions 15 at the ends of the visor and thus at the sides of the cap. The rear part of the cap, behind the loose portions 15, is provided with a rear sweat band 16 and in front of these portions 15 there is also a front sweat band 17.

Just to the rear of each end of the visor the head band is provided with a V-shaped notch 18 and to the rear edge of each notch is sewed the rear end of an adjusting strap 19 which passes out of the respective notch and forward over the outside surface of the cap adjacent the forward edge of the notch. Just forward of each notch and above the respective end portions of the visor is a slot 20 having rows of stitching 20' at the sides thereof and through which the strap 19 passes again into the inside of the cap, the remainder of the strap lying between the lining 13 and terminating opposite the loose portion 14 and thus being held beneath the front sweat band 17. The ends of the two straps overlap and are provided with cooperating adjusting and fastening means here shown as a hook 21 on one band and a series of eyelets 22 on the other band, the eyelets being spaced and provided with associated size indicia 23.

In the form shown in Figure 8 the arrangement is suitable for an unlined cap, the lining of course being shown as omitted. In this form the sweat band 16 of the previous form is shown as replaced by a rear sweat band 16' which is not only stitched to the cap proper but also extends forwardly along and is stitched to the adjusting straps 19 so that its ends pass beneath the ends of the front sweat band 17 through the slots 20 as may be seen by reference to Figure 6. Otherwise the cap is like the first form. Thus the

adjusting strap is not normally visible from the interior of the cap and of course no adjustment means can be seen from the exterior in this form just as the adjustment means is invisible in the first form.

Obviously, the cap is adjusted for size by engaging the hook in the appropriate eyelet and it is to be understood that any other suitable means, such for instance as snap button parts, may be used and that the invention is not limited to the particular fasteners here shown.

By reason of the notches 18 the cap may be contracted in size without producing any fullness or wrinkles in the head band proper while the rear ends of the straps 19 cover the notches and prevent any unsightly appearance at these points. Moreover, by reason of the slots 20 and the passage of the straps therethrough there is also prevented any disclosure of the adjusting means which is hid beneath both the lining and the front sweat band. Nevertheless, the arrangement of the loose part 14 affords ready access to the adjusting means when adjustment is desired.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In an adjustable cap, a head band portion having notches extending up from its bottom edge at the sides of the band, adjusting straps having their rear ends secured to the rear edges of said notches and extending within the cap and along the forward part of the head band portion, connecting means to connect the free ends of said straps adjustably, and a lining for said cap sewed at its edge to the bottom of the head band for the greater part of its length and having its edge free opposite the connecting means, the free edge portion covering the proximal ends of the straps.

2. In an adjustable cap, a head band portion having notches extending up from its bottom edge at the sides of the band, adjusting straps having their rear ends secured to the rear edges of said notches and extending within the cap and along the forward part of the head band portion, connecting means to connect the free ends of said straps adjustably, a lining for said cap sewed at its edge to the bottom of the head band for the greater part of its length and having its edge free opposite the connecting means, the free edge

portion covering the proximal ends of the straps, and a sweat band sewed to the lower edge of the cap and covering the free edged portion of the lining.

3. In an adjustable cap, a head band portion having notches extending up from its bottom edge at the sides of the cap and provided with slots each spaced forward of the respective notch, adjusting straps extending forward from the rear edges of said notches and overlapping the forward edge portions of said notches, said straps extending inwardly through said slots and along the forward part of the head portion, connecting means to connect the free ends of said straps adjustably, and a lining for said cap sewed at its edge to the bottom of the head band for the greater part of its length and having its edge free opposite the connecting means, the free edge portion covering the proximal ends of the straps. 80 85 90

4. In an adjustable cap, a head band portion having notches extending up from its bottom edge at the sides of the cap and provided with slots each spaced forward of the respective notch, adjusting straps extending forward from the rear edges of said notches and overlapping the forward edge portions of said notches, said straps extending inwardly through said slots and along the forward part of the head portion, connecting means to connect the free ends of said straps adjustably, a lining for said cap sewed at its edge to the bottom of the head band for the greater part of the length and having its edge free opposite the connecting means, the free edge portion covering the proximal ends of the straps, 100 105 110

and a sweat band sewed to the lower edge of the cap and covering the free edged portion of the lining. 115 120 125 130 135 140 145 150

5. A cap of the kind described having a head band consisting of a rear portion and a front portion, the head band having notches at the junction of said rear and front portions, said front portion being provided with slots each adjacent a respective notch and each extending straight through the head band to afford communication between the outside and inside of the cap, a sweat band carried by said front portion of the head band, adjusting straps connected to the rear portion of the head band and extending across the notches and over the front portion of the head band to said slots, said straps extending through the slots into the interior of the cap and having their ends located between the sweat band and the front portion of the head band, and means within the cap to secure said ends in adjusted relation to each other, whereby the adjusting means is accessible from the inside of the cap. 155 160 165 170 175 180 185 190 195 200
